UNITED STATES PATENT OFFICE.

CHRISTOPHER C. COOPER, OF ROBY, TEXAS.

DEVICE FOR PRINTING BLUE-PRINTS.

1,303,774.

Specification of Letters Patent. Patented May 13, 1919.

Application filed January 30, 1919. Serial No. 274,049.

To all whom it may concern:

Be it known that I, CHRISTOPHER C. COOPER, a citizen of the United States, residing at Roby, in the county of Fisher and State of Texas, have invented certain new and useful Improvements in Devices for Printing Blue-Prints, of which the following is a specification.

The present invention comprehends generally improvements in that class of inventions known as photography and more particularly relates to a device for printing blue prints.

It is the primary aim and object of this invention to provide a device of the above mentioned character embodying a curved supporting board with the respective ends of which are associated clamping means designed for engagement with the end of a map, picture or blue print and a sheet of sensitized paper for securing a perfect contact of the map, et cetera, with the surface of the board and in consequence produce an effective print.

More particularly the present invention contemplates the provision of a device of the above mentioned character wherein both of the clamps are of novel construction, one being stationary relative to the board while the other is adjustable to insure of the accommodation of various sized maps, pictures, et cetera, on the board.

Among the other aims and objects of this invention may be recited the provision of a device of the above mentioned character wherein the number of parts are comparatively few, the construction simple, the cost of production low and the efficiency high.

Other objects, as well as the nature, characteristic features and scope of this invention will be more readily apparent from the following description taken in connection with the accompanying drawings and pointed out in the claims, forming a part of this specification.

The invention is clearly illustrated in the accompanying drawings, in which:

Figure 1 is a perspective view of the improved device,

Fig. 2 is a side elevation thereof, and

Fig. 3 is a transverse sectional detail taken on line 3—3 of Fig. 2.

Similar characters of reference are employed in all of the above described views, 55 to indicate corresponding parts.

Referring now, more particularly, to the accompanying drawings, there is provided a supporting board 1 of a rectangular configuration in plan but curved longitudinally of its length and provided with a smooth outer surface. A sheet of sensitized paper 2 is adapted to be placed in contacting relation with the smooth outer surface of the board 1 while lying over the face of the paper is a map picture or blue print 3 desirably of the same size, both of the sheets being desirably of a width less than the width of the board.

In order to provide the improved stationary clamping means, a transversely disposed clamping bar 4 is employed having anchored therein the outer ends of upwardly arched or bowed resilient arms 5, the inner ends of which are carried with an attaching plate 6 in turn secured to the outer surface of the board medially of the side edges thereof to a suitable fastener such as a screw 7 so that the arms 5 will be tensioned to yieldingly hold the clamping bar 4 across the sheet 3 near one end thereof so that as a result both of the sheets 3 and 2 will be held in the proper contacting relation with each other and with the board 1. A grip handle 8 is connected to the bar 4 to facilitate the raising of the clamping bar when it is desired to remove the sheets 2 and 3 from the board.

As intimated, adjustable clamping means has been employed for coacting with the stationary clamping means in effecting a perfect contact of the map with the outer curved surface of the board preventing a wrinkling of the sheet and in effect producing an effective print. In reducing this feature of the invention to practice, a pair of clamping members generally indicated by the numeral 9 are employed each member consisting of a relatively wide engaging jaw 10 from the rear edge of which and medially of the ends thereof extends a handle 11, the ends of the jaws being formed with opposed ears 12 through which a pintle 13 is passed for pivotally connecting the members together while suitable resilient means such as a coil spring 14 is arranged about the pintle and has its respective ends positioned so as to exert a tension on the jaws 10 and hold them in yielding engagement with each other and to insure of the retention of the opposite ends of the sheets 2 and 3 when the latter are placed between the jaws. In exert-

ing a tension on the sheets 2 and 3, suitable resilient means such as a coiled contractile spring 15 is employed one end 16 being secured about the pindle 13 medially of the 5 ends thereof while the opposite end terminates in a hook 17 which coacts with a suitable flexible element 18 including a cable 19 in which is fitted at suitably spaced intervals a plurality of rings 20, one end of the 10 element 18 being anchored as at 21 to the opposite end of the board so that any one of the rings 20 may be engaged with the hook 17 and as a result insure of a variable tension on the sheets 2 and 3 when the device is 15 in use. It is believed to be apparent that by the provision of the adjustable tension clamp 9 that various sized maps, pictures, et cetera, may be printed.

It is believed in view of the foregoing description that a further detailed description of the operation of the invention is entirely unnecessary. Likewise, it is believed that the advantages of the invention will be readily apparent.

25 Still further embodiments of the invention than those herein especially defined may be resorted to as conditions or preference may dictate, as may be in keeping with the hereto appended claims.

30 Having thus fully described the invention, what is claimed as new and desired to be secured by Letters Patent, is:—

1. A printing device of the character described including a support having a curved 35 and smooth outer surface, a stationary sheet engaging clamp at one end of the curved surface of the support, and another sheet engaging clamp adjustably connected with

the support at a point opposite the stationary clamp.

2. A printing device of the character described including a longitudinally curved board having a smooth outer surface, a resiliently actuated sheet clamping bar secured to one end of the board, another sheet engaging clamp opposed to the first mentioned clamp, a resilient member connected to the last mentioned clamp, and a flexible element anchored to the opposite end of the board for removable and adjustable engagement 50 with the resilient member.

3. A printing device of the character described including a curved board having a smooth outer surface over which is adapted to be respectively placed in contacting and superposed relation a sheet of drawing and a sheet of sensitized paper, a stationary clamp including an attaching plate fastened to one end of the board, resilient arms extending from the plate, a clamping bar carried by 60 the arms for holding adjacent ends of the sheets against the board, another clamp engaged with the opposite ends of the sheets, a contractile spring connected to the last mentioned clamp, a hook at the outer end of the spring, a flexible element having one end anchored to the opposite end of the board and having its main portion adjustably engaged with the hook to in consequence exert a tension on the sheets and hold 70 them in smooth contacting relation with the board.

In testimony whereof, I affix my signature hereto.

CHRISTOPHER C. COOPER.
